UNITED STATES PATENT OFFICE.

WILLIAM SCHNELL, OF DETROIT, MICHIGAN, ASSIGNOR TO TERNSTEDT MANUFACTURING CO., OF DETROIT, MICHIGAN, A CORPORATION OF MICHIGAN.

DESIGN FOR AN AUTOMOBILE ROBE-RAIL FIXTURE.

Application filed May 10, 1924. Serial No. 9,546. Term of patent 14 years.

To all whom it may concern:

Be it known that I, WILLIAM SCHNELL, a citizen of the United States, residing at Detroit, in the county of Wayne and State of Michigan, have invented a new, ornamental, and original Design for Automobile Robe-Rail Fixture, of which the following is a specification, reference being had to the accompanying drawing, forming part thereof.

Fig. 1 is a front elevation of an automobile robe rail fixture embodying my new design.

Fig. 2 is a top plan view thereof.

I claim:

The ornamental design for an automobile robe-rail fixture, as shown.

WILLIAM SCHNELL.
